COMBINED CIGARETTE DISPLAY AND VENDING RACK

Peter Mihos, 278 Spring St., Brockton, Mass. 02401

Filed Aug. 18, 1975, Ser. No. 605,623

Term of patent 14 years

Int. Cl. D6—04; D20—02

U.S. Cl. D6—113

FIG. 5

FIG. 3

FIG. 4

FIG. 6

FIG. 7

FIG. 1 is a reduced perspective view of a combined cigarette display and vending rack showing my new design, as seen from the display side;

FIG. 2 is a front elevational view of FIG. 1;

FIG. 3 is a side elevational view taken from the left of FIG. 2;

FIG. 4 is a top plan view thereof;

FIG. 5 is a reduced bottom plan view thereof;

FIG. 6 is a rear elevational view as seen from the vending side; and

FIG. 7 is a side elevational view as seen from the left of FIG. 6.

The claimed rack is suspended from the ceiling or

other overhead structure by conventional supporting means in its normal environment.

I claim:

The ornamental design for a combined cigarette display and vending rack, as shown and described.
